EAVES TROUGH HANGER

Aaron Cohn, Philadelphia, Pa.

Application February 3, 1950, Serial No. 142,170

3 Claims. (Cl. 248—48.1)

1

The present invention relates to an eavestrough hanger. More particularly the invention relates to a hanger of the type embodying a bridge portion constituting a spacing and supporting arm extendable between the opposite upper edges of an eavestrough and a roof strap adapted for attachment to the roof.

The invention specifically relates to an improved coupling between the roof strap and the bridge portion.

Accordingly the invention has for an object to provide in an eavestrough hanger a structure that is characterized by ease of installation and positive locking of the roof strap to the bridge portion.

An additional object is to provide an auxiliary reinforced link greatly strengthening the union of the roof strap with the bridge portion.

A more specific object is to provide a particular reinforce link enhancing the durability of the hanger and one that does not restrict the rotation of the roof strap so as to provide for ease of installation.

With the above ends in view, my invention consists in an eavestrough hanger having certain details of construction and combinations of parts as will be hereinafter described and specifically indicated in the claims.

In the accompanying drawings:

Fig. 1 is a perspective view of my improved eavestrough hanger, as it appears prior to installation.

Fig. 2 is a side elevation of my hanger as it appears after application to an eavestrough, which is shown in transverse section.

Fig. 3 is a perspective view of the detached bridge member.

Fig. 4 is a perspective view of the detached cradle member.

Fig. 5 is a perspective view of the detached roof strap member.

Fig. 6 is a perspective view of the detached reinforce link member.

Fig. 7 is a longitudinal section through fragment A—A of Fig. 2.

Fig. 8 is a longitudinal section through fragment B—B of Fig. 2.

Referring particularly to the drawings, as shown in Fig. 3, the center portion of bridge 1 is bent downwardly along both edges to make reinforcing ribs 2, and has rivet holes 3 and 4 and a transverse reinforce link receiving slot 5 in its upper surface. One extremity of bridge 1 is formed into a transverse downwardly turned U-shape portion 6 conforming to the upper portion

2

of a trough bead 7, and is provided with a hinge opening 8, the lower edge of which is parallel to the inwardly flanged end 9 of the U-shaped portion. The other extremity of bridge 1 is formed into a downwardly turned hook 10 adapted to fit over the inner edge 11 of a trough, and which hook is provided with a transverse slot 12 at its apex to receive the end of the cradle after it has passed beneath the trough.

10 As shown in Fig. 4, a cradle 13 is of the same width throughout its length, has one end 14 bent transversely at an approximate 90 degree angle to the main body, and one portion of this end 14 is shaped to conform to the lower portion of trough 15 bead 7. The extremity of the same end is formed into an inwardly turned round hook 15. The other end 16 of cradle 13 is cut off squarely.

As shown in Fig. 5, roof strap 17 is of the same width throughout its length. One end 18, which 20 is cut off squarely, has nail holes 19 centered on its width. The other end 20 is rounded transversely to a true radius, with a rivet hole 21 therein, that is centered equidistant from sides and end.

25 As shown in Fig. 6, reinforce link 22 has one wider end 23 which is rounded transversely to a true radius, with a rivet hole 24 provided therein and centered equidistant from the sides and end thereof. The other and narrower end 25 is cut off squarely, is on a lower plane and has a centered rivet hole 26. Between the two planes is an intermediate portion providing a vertical step 27, and the difference in width between the ends is effected near the lower end of the step by the 30 provision of horizontal shoulders 28 extending inwardly from both edges of the vertical portion 27.

Reinforce link 22 is attached to bridge 1 by facing its wide end 23 in direction of bridge end 6, then inserting its narrow end 25 downwardly through bridge slot 5 until insertion is stopped by engagement of reinforce link horizontal shoulders 28 with the bridge surface, after which reinforce link 22 is riveted to bridge 1 through link 40 rivet hole 26 and directly superimposed bridge portion 6. Cradle 13 is linked in a hinge-like manner to bridge 1 by hanging cradle hook 15 on lower edge of bridge hinge opening 8 so cradle portion 14 is directly under bridge inverted U-shaped portion 6 and then closing hook 15 until it contacts the undersurface of portion 14. Roof strap 17 is attached to bridge 1 by inserting its end 20 under already attached reinforce link end 23 until roof strap rivet hole 21 is directly below reinforce link rivet hole 24 and directly above

bridge rivet hole 3, then the assembly is secured by rivet 29 passing through the three holes.

To install my hanger, cradle end 16 is raised until cradle portion 14 is vertical, providing clearance for admission of trough bead 7, then cradle end 16 is lowered until cradle portion 14 contacts the underside of trough bead 7, thereby clamping trough bead 7 between conforming jaws. Cradle end 16 is then passed under the trough and threaded through bridge slot 12 until cradle 13 conforms to the outer surface of the trough, then turned down as in Fig. 2. Roof strap 17 is given a return bend as in Fig. 2, rotated to the required position and roof strap end 18 nailed to the roof through roof strap holes 19.

It is therefore seen that I have provided in an eavestrough hanger, a bridge portion constituting a spacing and supporting arm which is provided with a transverse slot substantially intermediate the ends thereof and which bridge portion cooperates with the upper edges of an eavestrough. While the particular trough embodied as an example in the drawings is of round section, it is of course understood that the invention is applicable to those troughs of box section, suitable modification of the opposite ends of the bridge portion being required. My invention relates to the combination with a bridge member of a reinforce link and a roof strap. As indicated and described the reinforce link embodies three distinct portions, upper and lower horizontal end portions disposed in different planes and respectively above and beneath the bridge portion and an intermediate portion connecting the end portions and which intermediate portion has a length greater than the thickness of the roof strap and the flat horizontal portion of the bridge member so as to dispose the upper end portion of the reinforcing link a distance above the bridge portion sufficient to accommodate a roof strap. As indicated, a rivet passes through at least one of the horizontal end portions, the interposed roof strap and the bridge portion to secure the assembly together and to not only provide for reinforcement, since the strain is transmitted directly to the upper end portion 23 of the reinforce link rather than directly to the rivet head as customary, but which arrangement also provides for rotation of the roof strap relative to the bridge member through an arc of at least 90° to either side of the bridge member and thereby a total arc of not less than 180° and which arrangement of course provides for ease of installation. It is further noted that the reinforce link is provided with shoulders extending inwardly from opposite sides thereof to define different widths of the end portions. The upper end portion being wider than the slot in the bridge portion so that the shoulders constitute abutment surfaces to limit the insertion of the reinforce link through the slot in the bridge portion.

I claim:

1. In an eavestrough hanger, the combination of a bridge portion, a roof strap member and a reinforce link member, said reinforce link member comprising a central vertical portion and upper and lower horizontal end portions, said bridge portion having a transverse slot therein and said vertical portion passing through said transverse slot, said lower horizontal end portion being in contact with the under surface of said bridge portion, said upper horizontal end portion being spaced sufficiently above the upper surface of said bridge portion to admit one end of said roof strap between the under surface of said

upper horizontal end portion and the upper surface of said bridge portion, and a rivet passing through at least one horizontal portion of said reinforce link, said roof strap and said bridge portion to secure said combination together so that said roof strap can rotate through an arc of not less than 90° to either side of said bridge portion or through a total arc of not less than 180°.

10 2. In an eavestrough hanger the combination of a bridge portion, a roof strap member and a reinforce link member, said reinforce link comprising a central vertical portion and oppositely extending upper and lower horizontal end portions, said lower end portion being secured to the under side of the bridge portion, said bridge portion having a transverse slot therein and said central vertical portion passing through said slot, said upper end portion being substantially parallel to and spaced sufficiently above said bridge portion to admit one end of said roof strap and a rivet passing through said upper end portion of said reinforce link, said intermediate roof strap and said underlying bridge portion to secure said combination together so that said roof strap can rotate through an arc of not less than 90° to either side of the bridge or a total arc of not less than 180°.

3. In an eavestrough hanger, the combination of a bridge portion constituting a spacing and supporting arm and extendable between the opposite upper edges of an eavestrough, a roof strap member and a reinforce link member, said bridge portion having a transverse slot therein substantially intermediate the ends thereof, said reinforce link being of stepped shaped configuration in cross section and embodying upper and lower oppositely extending end portions and an intermediate portion connecting the end portions, the upper end portion being of greater width than the width of the slot in the bridge portion, the intermediate portion having shoulders extending inwardly from opposite edges thereof to define a reduced width, and said reduced width extending from the shoulders throughout the remaining area of said intermediate portion and the lower end portion, whereby the amount of insertion of said lower end portion into said slot is limited by the engagement of said shoulders with the upper face of said bridge portion, said lower end portion underlying and secured to said bridge portion and said intermediate portion having an extent greater than the combined thickness of said bridge portion and said roof strap so as to dispose said upper end portion a distance above the face of the bridge portion sufficient to receive one end of said roof strap, said end of said roof strap being disposed between said bridge portion and said upper end portion and a rivet passing through said upper end portion, said roof strap and said bridge portion to secure said combination together whereby said roof strap can rotate through an arc of not less than 90° to either side of said bridge portion or a total arc of not less than 180°.
